UNITED STATES PATENT OFFICE.

GEORGE C. LUNT, OF GREENFIELD, MASSACHUSETTS, ASSIGNOR TO THE
A. F. TOWLE & SON COMPANY, OF SAME PLACE.

DESIGN FOR A SPOON OR FORK.

SPECIFICATION forming part of Design No. 24,442, dated July 2, 1895.

Application filed June 6, 1895. Serial No. 551,910. Term of patent 7 years.

To all whom it may concern:

Be it known that I, GEORGE C. LUNT, a citizen of the United States, residing at Greenfield, in the county of Franklin and State of Massachusetts, have invented and produced new and original Design for a Spoon or Fork Handle, of which the following is a specification, reference being had to the accompanying drawings, which form a part of the same.

This invention relates to a design formed upon the handle of a spoon, fork, or similar article; and it consists in an ornamental configuration herein shown and claimed.

Figure 1 of the accompanying drawings represents a front view of a spoon or a fork, as indicated by dotted lines, containing my ornamental design. Fig. 2 represents a side or edge view thereof.

The ornamental configuration constituting my design is applied to the front or face of the handle of a spoon or fork, as indicated by dotted lines, or similar article.

The handle A' extends outward from the bowl A, at first in slightly-curving converging lines, then in nearly parallel lines, defined on each side by the marginal beads a a, up to the leafwork c, where the outline swells outward on each side at e e, and is then curved inward on each side at f f and then outward at the leafwork g g on each side at the top of the handle. Within the marginal beads a a and parallel thereto are two longitudinal beads a' a', which terminate at the base or lower ends in inwardly-turned scrolls. Between the terminal scrolls of beads a' a' is a three-part leaf b. The interior beads a' a' are formed with outwardly-turned scroll and leafwork c at the base of the outward curves or enlargements e e, the points of such leaf-

work turning over onto the marginal beads a a, as shown. Just above the lateral swells or enlargements e e the marginal beads a a are formed with inwardly-turned scroll and leafwork d d, the points of which turn over onto the inner beads and upon the body of the handle, extending upward into the inner curves f f of the handle, as shown. The inner and outer beads a' a' follow the inwardly-curved contour f f, and also extend, partly hidden by the leafwork, to the top of the handle. The handle terminates at its tip with an upwardly-turned scalloped shell h. On each side of the shell h the outwardly-swelling contour of the handle is ornamented with scroll-like stems g' g' and leafwork g g, having numerous inwardly-curved points, which overlap the lateral beads and lie upon the interior body of the handle, as shown. Just below the shell h, and between the lateral leaves g g, there is formed the central leaf k, having numerously outwardly-curved lateral points and a downwardly-extending central point lying upon the body of the handle, and also having a central longitudinal line of small knobs or beads, as shown.

Having described my invention, what I claim, and desire to secure by Letters Patent, is—

The design for spoons, forks and similar articles consisting of the ornamental configuration on the front of the handle, substantially as shown.

In testimony whereof I affix my signature in presence of two witnesses.

GEO. C. LUNT.
